Written Opinion issued Dec. 14, 2015 in PCT/IB2015/056493.

Primary Examiner — Austin Murphy(74) *Attorney, Agent, or Firm* — Polsinelli PC(57) **CLAIM**

The ornamental design for a personal monitor, as shown and described.

DESCRIPTION

FIG. 1 is a front perspective view of the personal monitor showing our new design, with a clip of the personal monitor closed;

FIG. 2 is a rear perspective view thereof;

FIG. 3 is a top view thereof;

FIG. 4 is a bottom view thereof;

FIG. 5 is a left side view thereof, being a mirror image of the right side thereof;

FIG. 6 is a rear view thereof;

FIG. 7 is a front view thereof;

FIG. 8 is a front perspective view of the personal monitor showing our new design, with the clip of the personal monitor open;

FIG. 9 is a rear perspective view thereof; and,

FIG. 10 is a left side view thereof, being a mirror image of the right side thereof.

The personal monitor as shown has a C-shaped lever and a C-shaped jaw, which pivot simultaneously in opposite directions.
